US0D1069934S

(12) **United States Design Patent** (10) **Patent No.:** **US D1,069,934 S**
(45) **Date of Patent:** **** Apr. 8, 2025**

(54) **MODEL VEHICLE BUMPER**

(71) Applicant: **TRAXXAS, L.P.**, McKinney, TX (US)

(72) Inventors: **Adam Cole Ewing**, McKinney, TX (US); **Terry Soward**, Van Alstyne, TX (US)

(73) Assignee: **TRAXXAS, L.P.**, McKinney, TX (US)

(**) Term: **15 Years**

(21) Appl. No.: **29/897,325**

(22) Filed: **Jul. 13, 2023**

(51) **LOC (15) Cl.** **21-01**

(52) **U.S. Cl.**

USPC **D21/561**; D12/169

(58) **Field of Classification Search**

USPC D12/86, 88, 90, 91, 92, 163, 164, 167, D12/169, 170, 172, 196; D21/433, 434, D21/533, 548, 562, 424, 483, 495, 552, D21/561

CPC B62D 25/08; B60R 19/02; B60R 19/04; B60R 19/52; B60R 2019/1886

See application file for complete search history.

(57) **CLAIM**

The ornamental design for a model vehicle bumper as shown and described.

DESCRIPTION

FIG. 1 is an upper, left, front perspective view of a model vehicle bumper showing our new design; FIG. 2 is a lower, right, front perspective view thereof; FIG. 3 is a lower, left, rear perspective view thereof; FIG. 4 is an upper, right, rear perspective view thereof; FIG. 5 is a front elevation view thereof; FIG. 6 is a rear elevation view thereof; FIG. 7 is a right side elevation view thereof; FIG. 8 is a left side elevation view thereof; FIG. 9 is an upper plan view thereof; and, FIG. 10 is a lower plan view of the model vehicle bumper. In the drawings, the broken lines illustrate portions of the model vehicle bumper that form no part of the claimed design.

1 Claim, 5 Drawing Sheets
